(57) **CLAIM**

The ornamental design for a divider for vehicle light bar, as shown and described.

DESCRIPTION

FIG. 1 is a perspective view of a divider for vehicle light bar showing our new design in an unlock position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a divider for vehicle light bar in FIG. 1 in a lock position;

FIG. 9 is a front view in FIG. 8;

FIG. 10 is a rear view in FIG. 8;

FIG. 11 is a left view in FIG. 8;

FIG. 12 is a right view in FIG. 8;

FIG. 13 is a top view in FIG. 8;

FIG. 14 is a bottom view in FIG. 8;

FIG. 15 is a reference view of a divider setting in a vehicle light bar;

FIG. 16 is a reference view of a divider setting in a vehicle light bar in an unlock position; and,

FIG. 17 is a reference view of a divider setting in a vehicle light bar in a lock position.

The broken lines depict portions of the vehicle light bar that form no part of the claimed design.
